HARRY E. NORVIEL, OF ANDERSON, INDIANA, ASSIGNOR TO DELCO-REMY CORPORATION, OF DAYTON, OHIO, A CORPORATION OF DELAWARE

LOCK SWITCH

Original application filed March 25, 1926, Serial No. 97,457. Divided and this application filed January 28, 1928. Serial No. 250,104.

This invention relates to lock switches and particularly to lock switches for use in connection with the ignition system of an automobile. This application is a division 5 of copending application Serial No. 97,457, filed March 25, 1926, and covers ignition apparatus comprising a novel combination of ignition coil and lock switch.

One object of the present invention is to 10 provide an improved key operated device for operating the switch and for preventing the unauthorized opening of the switch case. While the present invention is embodied in a combined switch and coil structure which is the subject of the copending application referred to it will be apparent from the following description that the present invention is susceptible of embodiment in a structure in which the ignition coil is 20 not present.

In the drawings:

Fig. 1 is a fragmentary sectional view of a unitary coil and switch structure constructed in accordance with the present invention.

Fig. 2 is an end view looking in the direction of arrow 2 in Fig. 1.

Fig. 3 is a fragmentary longitudinal section view on the line 3—3 of Fig. 2.

Fig. 4 is an end view, partly in section, looking in the direction of arrow 4 of Fig. 1, showing the coil and switch unit removed from its mounting bracket, the section through the switch case being taken on the line 4—4 of Fig. 3.

Fig. 5 is an end view on the line 5—5 of Fig. 1 of the ignition coil after being disassembled from the switch case.

Fig. 6 is a fragmentary view on the line 40 6—6 of Fig. 1.

While not essential to the construction and operation of the lock switch embodying the present invention, this switch can be used to advantage in a structure in which 45 a part of the switch case is provided by part of an ignition coil housing, a fragment of which is shown in longitudinal section in Figs. 1 and 3. The coil housing comprises a metallic tubular portion 20 permanently attached to metallic end covers one

of which is shown at 22. The housing 20 encloses a core 33 surrounded by a secondary winding 29 and a primary winding 28. One end of the core 33, which is formed preferably by a bundle of relatively small iron wires is received by a recess 35 in a non-conducting block 36 which is maintained in the position shown between the core 33 and the end cover 22 after the coil has been assembled. 55

The ignition coil is combined in a unitary structure with a switch having a case 40, for which the ignition coil provides a cover. The coil is attached to the case 40 by means including a ring 41 permanently attached to the housing member 20 and having a flange 42 which is attached by rivets 43 to a flange 44 of the switch case 40. The cylinder member 45 of a pin tumbler lock is provided with arms 46 which are attached by screws 47 to the switch case 40 which is provided with an aperture suitable for receiving the cylinder 45. The cylinder 45 supports a rotatable key plug 48 for receiving a proper key 49 by which the key plug 48 may be turned. A plate 50 is attached by screws 51 to the plug 48 and is attached by rivets 52 to a non-conducting plate 53 provided with a metallic insert 54 which is attached to the plate 53 preferably by molding the material of the plate about the insert. The conductor 54 constitutes the movable contact of the ignition switch and is provided with holes or depressions 55 for receiving the somewhat spherical projections 56 formed on the free ends of leaf spring conductors 57. The conductors 57 are received by grooves 58 provided in a somewhat oblong shaped boss 59 formed integral with the insulating body 36 and projecting through a similarly shaped opening in the coil housing member 22. The contact plates 57 are secured by hollow rivets 60 through which connections are made between the contacts 57 and the ignition primary coil 28. These connections are provided by winding one more turn than necessary in the last or outside layer of turns of the primary coil 28. The turn of the outside layer which is nearest the insulating body 36 is cut at its middle point to provide 60 70 75 80 85

90 95 100

two wires 61 and 62 which connect respectively the outside layer of the primary coil 28 and the preceding inside layer with one of the switch contacts 57.

- 5 If the movable contact 54 is turned 90° from the position shown in Figs. 1, 4 and 6 it will be engaged by the contacts 57, the spherical ends 56 snapping into the holes 55 of the contact 54. This operation will 10 connect a current source with the ignition coil primary winding 28 and with an ignition timer, not shown, so that when a timer is operated by an internal combustion engine sparking impulses will be generated by 15 high voltage in the secondary coil 29, and these impulses will be distributed to the arc plugs of the engine by suitable distributing apparatus, not shown. Turning the key 49 to the position shown in Figs. 1 and 3 will 20 cause the contact 54 to be disengaged from the contacts 57 so that the ignition apparatus will be rendered inoperative and the engine will stop. When the key is in this latter position it may be removed from the 25 lock. Hence the ignition switch cannot be operated without the proper key.

In order to prevent disassembling of the ignition coil from the switch case 40 while the ignition switch is locked in "off" position, means are provided for rendering the rivets 43 inaccessible to such tools as a chisel by which the heads of the rivets could be removed. This means includes a mounting bracket 80 to which the coil and switch assembly is attached by screws 81 which pass through plain holes in the flanges 42 and 44 and through tapped holes in the bracket 80. The bracket 80 comprises a central disc portion 80a which merges into an annulus 80b of channel shaped cross section and then into a circular flange 80c. The flange 80c is permanently attached to the instrument or dash board of the vehicle. If a thin metal dash is used alone without a wooden backing as indicated at 82 in Fig. 1, the flange 80c is secured to the dash by welding or brazing. But if a wooden backing 83 is used the flange 80c may be secured by screws 84 to the wooden backing 83, and the heads 50 of the screws 84 will be covered by the metal dash 82.

The wall 85 forming a part of the channel shaped section 80b of bracket 80 is provided with a number of holes 86 for receiving the heads of the rivets 43. Although the screws 81 may be removed, the coil and switch assembly cannot be removed from the bracket 80 while the ignition switch is locked "off" position. This is accomplished 55 by lock controlled device including studs 90 mounted on leaf spring members 91 attached at 92 to the switch case 40. The case 40 is provided with diametrically opposite holes 93 which are aligned with diametrically opposite holes 94 in the bracket 80. The holes

93 and 94 receive the studs 90 which, when in the position shown in Figs. 3 and 4, will prevent separation of the parts 40 and 80. When the switch is locked, the pins 90 will be held in locking position due to engagement thereof with lugs 95 which are provided by the non-conducting body 53. When the switch is turned to "on" position, the lugs 95 will be moved out of engagement with the studs 90 so that the springs 91 will be released to move the studs 90 inwardly and disengage them from the bracket 80. Then the switch and coil assembly may be removed from the bracket. In order to assist in locating the contact 54 in "off" and "on" positions, the plate 53 is provided with notches 96 and 97 for receiving the end 98 of a leaf spring 99 which is attached to the switch case 40.

In case the coil should fail to operate it is not necessary to discard the entire switch and coil unit. After removal of this unit from its bracket, the rivets 43 may be removed by a chisel or a drill and a new coil may be quickly substituted. The only parts of the switch which are discarded are the contacts 57. The lock and the more expensive parts of the switch remain assembled with the switch case.

While the form of embodiment of the present invention as herein disclosed, constitutes a preferred form, it is to be understood that other forms might be adopted, all coming within the scope of the claims which follow.

What is claimed is as follows:

1. An electric switch, comprising in combination, a switch case having separable members; means for attaching the members together; cooperating switch contacts within the case; means for rendering the attaching means inaccessible for removal; and key operated devices for controlling the engagement and disengagement of the contacts and for locking the switch case to the means which renders the attaching means inaccessible.

2. An electric switch such as defined by claim 1, in which the switch includes contacts connected respectively with the switch case members, the contacts being separable to permit separation of the case members when the switch is turned "on."

3. An electric switch such as defined by claim 1, in which the switch includes a relatively stationary contact connected with one of the case members and a movable contact connected with the other switch case member, and in which the locking means comprises key operated devices enclosed by the case for operating the movable contact and for preventing separation of the switch case members from the means which renders inaccessible the switch case attaching means

when the movable contact is turned to "off" position.

4. An electric switch according to claim 1, in which a mounting bracket renders the attaching means inaccessible, the switch case being locked to the bracket by the key operated device.

5. An electric switch according to claim 1, in which the switch case members are attached by headed rivets, and the means which is locked in operative position by the key operated device renders the heads of the rivets inaccessible.

6. An electric switch and a support therefor, comprising a bracket providing a cup-shaped recess, a switch case adapted to be received by the recess of the bracket, cooperating switch contacts within the case, a lock mounted within the case and having a key receiving member extending through aligned apertures in the end wall of the recess of the bracket and in the switch case, and devices operated by the lock for controlling the engagement and separation of the contacts and for preventing removal of the case from the bracket.

7. An electric switch, comprising in combination, a switch case having separable members; means for attaching the members together; cooperating switch contacts within the case; a mounting bracket for rendering the attaching means inaccessible for removal; and key operated devices for controlling the engagement and disengagement 35 of the contacts and for locking the switch case to the bracket.

8. The combination with an electric switch, of a mounting bracket providing a receptacle, a switch case receivable by said receptacle, cooperating contacts within the case, a lock controlled contact actuator within the case, and having a key barrel extending through the case and bracket, and devices operated by said lock controlled actuator for rendering the case and bracket 40 inseparable, yet permitting the separation thereof upon proper manipulation of the controlled devices.

9. An electric switch and a support therefor, comprising a bracket providing a cup-shaped recess, a switch case adapted to be received by the recess of the bracket, a lock mounted within the case and having a key receiving member extending through aligned apertures in the bracket and in the switch case, and devices operated by the lock for controlling said switch and for preventing removal of the case from the bracket.

10. The combination with an electric switch, of a mounting bracket providing a receptacle, a switch case receivable by said receptacle, a lock controlled actuator having a key barrel extending through the case and bracket, and devices operated by said lock

controlled actuator for rendering the case and bracket inseparable, yet permitting the separation thereof upon proper manipulation of the controlled devices.

5 In testimony whereof I hereunto affix my 70 signature.

HARRY E. NORVIEL.
